UNITED STATES PATENT OFFICE

JOHN J. HALTERBECK, OF LONG ISLAND CITY, NEW YORK

DESIGN FOR AN AQUARIUM

Application filed February 11, 1932. Serial No. 42,812. Term of patent 7 years.

To all whom it may concern:

Be it known that I, JOHN J. HALTERBECK, a citizen of the United States, and a resident of Long Island City, in the county of Queens and State of New York, have invented the new, original, and ornamental Design for an Aquarium, of which the following is a specification.

Reference is had to the accompanying drawings, forming part thereof, wherein—

Figure 1 is a perspective view of an aquarium showing my new design.

Figure 2 is an enlarged fragmentary sectional view through Figure 1 on line 2—2, illustrating the ornamental forma-

tion of the post.

I claim:

The ornamental design for an aquarium

substantially as shown and described.

JOHN J. HALTERBECK.
